UNITED STATES PATENT OFFICE.

ERNEST JAMES SMITH, OF CHICAGO, ILLINOIS, ASSIGNOR TO THE GOSS PRINTING PRESS COMPANY, OF CHICAGO, ILLINOIS, A CORPORATION OF ILLINOIS.

INKING MECHANISM.

1,272,135.

Specification of Letters Patent.

Patented July 9, 1918.

Application filed June 19, 1916. Serial No. 104,464.

To all whom it may concern:

Be it known that I, ERNEST JAMES SMITH, a subject of the King of England, and a resident of Chicago, in the county of Cook, 5 State of Illinois, have invented certain new and useful Improvements in Inking Mechanisms, of which the following is a specification, reference being had to the accompanying drawings.

10 My invention relates to inking mechanisms for printing presses and it has for one of its objects the provision of a new and improved form and arrangement of parts for moving certain of the inking rollers out of 15 operative position when the press is out of operation. It is one of the more specific objects of my invention to provide means for throwing the form rollers and the vibrating rollers simultaneously out of contact with 20 the inking cylinder and the form cylinder. It is another object of my invention to provide means for driving the inking cylinder independently of the operation of the press whereby the inking cylinder may be brought 25 to a properly inked-up condition prior to a run of the press. It is another object of my invention to improve mechanisms of this type in sundry details hereinafter pointed out. The preferred means by which I have 30 accomplished my several objects are illustrated in the drawings and are hereinafter specifically described. That which I believe to be new and desire to cover by this application is set forth in the claims.

35 In the drawings:—

Figure 1 is a view of a portion of a press embodying my improved form of inking mechanism;

Fig. 2 is a vertical cross-section, partly 40 broken away, through the inking mechanism, being taken substantially on line 2—2 of Fig. 1;

Fig. 3 is a vertical section taken on line 3—3 of Fig. 2; and

Fig. 4 is a vertical section taken on line 4—4 of Fig. 2.

Referring to the several figures of the drawings in which corresponding parts are indicated by the same reference characters,—

10 indicates the framework of a press having revolvably mounted thereon an inking cylinder 11, a form cylinder 12 and an impression cylinder 13 in proper relationship 55 to each other. Arms 14 are pivotally

mounted upon the frame 10 at opposite ends of the cylinder 11, having journaled between them a form roller 15. Two arms 16 are pivotally mounted on the frame 10 at opposite ends of the cylinder 11 having journaled between them a form roller 17 and a plurality of vibrating rollers 18. The arms 14 are held in position relative to the cylinders 11 and 12 by means of links 19 which are connected at their lower ends to the arms 14 60 and are connected at their upper ends to eccentrics 20 mounted upon a rock-shaft 21 above the cylinder 11, as shown in Fig. 2. The arms 16 are held in position by means of links 22 connected at their lower ends 65 with said arms and connected at their upper ends with eccentrics 23 likewise mounted upon the shaft 21. The form and arrangement of the parts is such that the rollers 15 and 17 are adapted to be thrown simultaneously into engagement with the cylinders 11 and 12 and are adapted in turn to be thrown simultaneously out of such engagement, the rollers 18 being thrown out of engagement with the cylinder 11 at the 70 same time when the form roller 17 is thrown out of engagement with the cylinders 11 and 12.

The rock-shaft 21 is utilized for supporting a gear 24 revolvably mounted thereon and 75 meshing with a gear 25 revolvably with the cylinder 12 and also meshing with a gear 26 revolvably mounted upon the shaft 27 by which the inking cylinder 11 is supported. The gear 26 is provided with a pawl 28 pivotally mounted thereon adapted to engage a ratchet-wheel 29 keyed or otherwise fixedly mounted upon the shaft 27 of the inking cylinder 11 so as to drive the ratchet-wheel and the inking cylinder in clockwise 95 direction in Fig. 1. The pawl 28 is pivotally connected by means of a link 30 with a controller 31 frictionally mounted upon the hub of the ratchet-wheel 29. By this construction, when the ratchet-wheel 29 is 100 driven in clockwise direction in Fig. 1 by power applied thereto independently of the pawl 28, the friction member 31 is given a slight rotation in clockwise direction in Fig. 1, serving to lift the pawl 28 out of engagement with the teeth of the ratchet-wheel 29. When power is applied to the gear 26 so as to rotate such gear in clockwise direction in Fig. 1 relative to the ratchet-wheel 29, the controller 31 tends to lag behind, serving to 105 110

throw the pawl 28 again into engagement with the teeth of the ratchet-wheel 29.

32 indicates an inking roller revolvably mounted upon a shaft 33 adjacent to the inking cylinder 11. An oscillating roller 34 is adapted to be reciprocated by any suitable means (not shown) between the inking roller 32 and the inking cylinder 11 so as to transfer ink from the roller 32 to the cylinder 11 in the well understood manner. Ink is adapted to be supplied to the roller 32 in the construction shown by a nozzle 35 through a supply pipe 36 from any suitable source, the ink-supplying means being preferably actuated by power from the means by which the roller 32 is normally driven. A scraper-blade 37 is provided for spreading the ink upon the roller 32 and for scraping the surplus ink therefrom, any ink so scraped from the roller being adapted to fall into a trough 37^a from which it is conducted by a pipe 38 to any suitable point. The inking roller 32 is adapted to be driven by means of a worm-gear 39 fixed upon the outer end of the shaft 33, being driven by a worm 40 fixed upon a shaft 41 driven by any suitable means in counterclockwise direction in Fig. 2, serving to rotate the inking roller 32 in clockwise direction in Fig. 1.

30 Means is provided for driving the inking cylinder 11 in clockwise direction in Fig. 1 independently of the action of the gear 26, comprising a sprocket-gear 42 fixedly connected with the ratchet-wheel 29 connected by means of a sprocket-chain 43 with a sprocket-wheel 44 having clutch connections with the shaft 33. The connections between the sprocket-wheel 44 and the shaft 33 comprises a clutch member 45 revolvably mounted upon the shaft and adapted to be driven in clockwise direction in Figs. 1 and 4 by a clutch member 46 keyed or otherwise fixed upon said shaft, the clutch member 45 being adapted to rotate in counterclockwise direction in Fig. 4 independently of the clutch member 46.

The means for driving the shaft 41 is in the construction shown in the form of a planetary gearing connected by means of 50 bevel-gears 47-48 with said shaft. The planetary gearing comprises a head 49 adapted to be driven in counter-clockwise direction from any suitable part of the press, having mounted thereon planet-gears 55 50-51 meshing with a sun-gear 52 which is connected by means of a short shaft 53 with the bevel-gear 47. An internal gear 54 revolvably mounted upon the axis of the sun-gear 52 meshes with planet-gears 50-51 and is adapted to be driven in clockwise direction in Fig. 1 by a motor 55 through the medium of a worm 56 meshing with suitable worm-gear teeth 57 formed upon the internal gear 54.

60 65 With the head 49 being driven in counter-

clockwise direction in Fig. 1 at the same speed of rotation as that of the form cylinders of the press,—say at 150 revolutions per minute,—and with the internal gear 54 being driven in clockwise direction in said figure at about 20 rotations per minute, the inking roller 32 will be driven in clockwise direction in said figure at a rate of about 24 or 25 rotations per minute. With the press running at low speed so that the head 49 will be driven in the counterclockwise direction in Fig. 1 at about 1/15 the high speed rate, or 10 revolutions per minute, and with the internal gear 54 rotating at its normal speed of 20 revolutions per minute, the roller 32 will be given approximately 3 1/2 rotations per minute, or at a rate of about 1/7 its speed of rotation when the press is running at full-speed. By the use of this arrangement a differential driving of the inking roller 32 is secured, the roller 32 being driven at a higher speed relative to that of the press when the press is running at low speed than when the press is operating at its normal high speed.

With the inking cylinder 11 being driven in clockwise direction in Fig. 1 through the gears 25-24-26, and with the inking roller 32 being driven in the same direction through the shaft 41, the sprocket-gear 39 is rotated in clockwise direction relative to the slowly-rotating roller 32, this result being attained by reason of the yielding of the clutch 45-46. When the press is at rest, and the rollers 15, 17 and 18 have been thrown out of engagement with the cylinder 11 and the cylinder 12, the motor 55 is adapted to drive the internal gear 54 in clockwise direction in Fig. 1, serving to drive the roller 32 at a slow rate independently of the head 49 which is maintained in fixed position. The clutch 45-46 then serves to connect the shaft 33 with the sprocket-wheel 44 for rotation of such sprocket-wheel in clockwise direction in Fig. 1, whereby the sprocket-wheel 42 and inking cylinder 11 are driven slowly in clockwise direction in Fig. 1 independently of the remainder of the press, the pawl 28 being adapted to permit rotation of the ratchet-wheel 29 in such a direction relative to the gear 26. In this manner the roller 32 and the inking cylinder 11 may be rotated and properly inked up ready for efficient operation of the press prior to starting the press into operation.

What I claim as my invention and desire to secure by Letters Patent, is—

1. The combination of an inking cylinder, a form cylinder parallel with said inking cylinder and out of contact therewith, two arms swingingly mounted relative to said inking cylinder at its ends, a form roller revolvably mounted on said arms at one side of the line of centers of said cylinder 125

ders, two other arms swingingly mounted relative to said inking cylinder at its ends, a second form roller revolvably mounted on said second-named arms on the opposite 5 side of the line of centers of said cylinders, a rock-shaft extending along said inking cylinder, and links pivotally connected with said arms and having eccentric connection with said rock-shaft whereby upon 10 the turning of said rock-shaft said form rollers are moved simultaneously either into or out of contact with said cylinders.

2. In an inking mechanism, the combination of an inking roller, means for delivering ink to said roller, and inking cylinder, 15

means for applying ink from said roller to said cylinder, means for driving said cylinder in one direction comprising a pawl and ratchet mechanism adapted to permit the cylinder to be driven independently in 20 the same direction, means for positively driving said inking roller, and a chain connected positively with said cylinder and connected by a one-way clutch mechanism with said inking roller adapted upon the 25 rotation of the roller to drive said cylinder but adapted to permit said cylinder to be driven at an increased speed in the same direction.

ERNEST JAMES SMITH.
